UNITED STATES PATENT OFFICE.

ARTHUR J. CAILLE, OF DETROIT, MICHIGAN.

DUAL IGNITION FOR OUTBOARD MOTORS.

Application filed December 30, 1925. Serial No. 78,317.

The present invention relates to ignition systems for internal combustion engines and more specifically for what are known as "outboard" motors.

5 Among the objects of the invention is to provide such engines with both magneto and battery ignition.

Another object is dual ignition for such motors in which the change from the battery 10 ignition to the magneto may be made with less chance of stalling the motor than in installations heretofore used.

With these and other objects in view, as will more clearly hereinafter appear, the 15 invention consists broadly in an engine provided with magneto ignition in which the low tension circuit is, at a convenient place, so arranged that, by the use of a simple mechanism, an exterior battery circuit may 20 be substituted therefor.

Reference should be made to the accompanying drawings, in which:—

Fig. 1 is a plan view of a well known 25 outboard motor and the battery assembly; Fig. 2 is an enlarged longitudinal section of the control handle and battery plug.

In the drawings, an outboard two cylinder motor is shown with the two opposed cylinders at 10 having spark plugs at 11 30 connected to the high tension side of the magneto by cables 12. The engine flywheel is shown at 15 and this carries on its under side a conventional flywheel magneto (not shown), controlled for timing by the handle 35 secured below the flywheel.

Handle 16 is shown in section in Fig. 2 and consists of a metal shell 17 which may be open at its under side and provided with a flattened surface 18 to permit its being 40 mounted by suitable bolts or screws. At an intermediate point there is mounted inside the handle the springs of a telephone jack indicated at 20, 21, 22 and 23 insulated from each other by the insulating spacers 45 24 and secured to the handle by screws 25 from which the springs are insulated by the spacers and another insulating piece 26. Spring 23 contacts with the handle. In the end of the handle is an insulating bushing 50 30, through which may be inserted an ordinary telephone plug 31 connected to the two poles of the battery 32 by wires 33 and 34, one of which 33 leads to the shaft of the plug and the other to the tip thereof.

55 Springs 22 and 23 of the jack are provided with contacts 35 normally in contact

with each other and the handle carries in its upper side a button 36 which may, by means of the extension 37, be used to separate contacts 35, this extension passing 60 freely through spring 23 into contact with spring 22. The button and extension are, of course, of non-conducting material.

The battery circuit is primarily for use in starting the engine and under these conditions the plug will be in the handle as indicated in Fig. 2. When the plug is in as shown the circuit will be from one pole of the battery through wire 33 to the plug shaft and to spring 20, then through a coiled 70 wire 40 to the end of spring 22 to which is also secured a wire 41 leading to the primary winding of the induction coil, the other end of which winding will be grounded to the engine. The other pole of the battery is 75 connected through wire 34 to the tip of the plug and thence to spring 23 which is grounded to complete the circuit.

When the plug is withdrawn, the contacts 35 come together and the completed 80 circuit including the low tension magneto winding is through the latter and then through wire 41 to spring 22, contacts 35, spring 23 to the handle and therefore to ground.

When the motor is operating on the magneto circuit, the latter may be broken and the motor stopped by separating contacts 35 by means of button 36. If the battery 90 circuit is being used, the plug must first be withdrawn before the circuit can be broken by button 36.

Coil 40 serves a dual purpose in the installation just described. It serves to connect wire 41 with spring 20 and also as a 95 resistance to limit the amount of current which may flow from the battery through the induction coil, thereby protecting the latter.

Having now described the invention and 100 the preferred form of embodiment thereof, it is to be understood that said invention is not to be limited to the specific details herein described and shown but only by the scope of the claims which follow.

Claims:

1. In combination with an internal combustion engine having a magneto including an induction coil for supplying high tension current, a closed circuit telephone jack in the circuit including said magneto and the primary winding, and an electric battery 110

- having its terminals connected to a telephone plug adapted to be inserted in said jack to open said magneto circuit and close a circuit including the battery.
5. An internal combustion engine having magneto ignition, a timer therefor having a handle, a closed circuit telephone jack in said handle, and a telephone plug connected to the two terminals of a battery, said jack and plug being constructed and arranged to co-act to insert said battery in the low tension circuit of said magneto.
- 10
3. An internal combustion engine having magneto ignition, a timer therefor having a handle, a closed circuit telephone jack in said handle, and a telephone plug connected to the two terminals of a battery, said jack and plug being constructed and arranged to co-act to insert said battery in the low tension circuit of said magneto and having a resistance element to limit the current supplied by said battery.

ARTHUR J. CAILLE.
